UNITED STATES PATENT OFFICE.

WILLIAM ERASTUS WILLIAMS, OF WILMETTE, ILLINOIS, ASSIGNOR TO AMERICAN STEEL FOUNDRIES, OF CHICAGO, ILLINOIS, A CORPORATION OF NEW JERSEY.

AUTOMOBILE WHEEL WITH DEMOUNTABLE RIM.

Application filed October 19, 1922. Serial No. 595,592.

To all whom it may concern:

Be it known that I, WILLIAM ERASTUS WILLIAMS, a citizen of the United States, and a resident of Wilmette, county of Cook, 5 State of Illinois, have invented a new and useful Improvement in Automobile Wheels with Demountable Rims, of which the following is a specification.

The object of my invention is to make 10 a demountable rim disc wheel that will be the cheapest and best for use with a quick detachable rim for a pneumatic tire.

Reference will be had to the accompanying drawings on which Figure 1 is an elevation of a part of a wheel.

Figure 2 is a section on line 2-2 of Figure 1.

Figure 3 is a section on line 3-3 of Figure 1.

20 Figure 4 is a sectional elevation on line 4-4 of Figure 1.

Figure 5 is a front elevation of a part of the side ring of the rim.

25 Figure 6 is a transverse section of the side ring on line 6-6 of Figure 5, showing the locating pin of the side ring.

Figure 7 is a section on the line 7-7, Figure 1.

In the drawings 1 indicates the inner 30 flange of a quick detachable tire rim 2. This rim 2 has a flange 3 which forms the side of the gutter 4 into which is retained the snap side ring 5 of a quick detachable pneumatic tire rim.

35 The web of the wheel is formed of a disc 6, the portion below the line 7 not being shown, but the disc may be curved in any desirable shape from its junction with the rim to the hub, crossing or not crossing the 40 medial line as may be desired by the wheel builder.

The disc 6 is turned over at its margin into contact with an inclined portion 9 which forms one wall of the gutter 4 of the rim 45 2. The flange 8 of the disc is merged over into a horizontal flange 10 for the purpose of stiffening the margin of the disc.

The detachable side ring 5 is split as shown at 11 in Figure 1 in order to permit

50 it to be sprung into and out of engagement with the gutter 4 of the rim 2. The ring 5 is positioned always in the same place on the rim 2 by a fixed pin 12 which engages a hole 13 in wall 9 of the gutter 4, see Figure 6.

55 The rim is apertured at 14 and counter-

bored at 15 at intervals. To accommodate the fastening screws 16 which pass through the gutter portion of the ring 5, flange 3 and wall 9 of the rim 2, the flange 3 and wall 9 are pierced for the passage of these bolts 16. 60 The flange 3 is counterbored at its upper corner 17 below the dotted lines of Figure 6 to coact with the counterbore 15 of the ring 5 to furnish the seat for the head of the screw 16.

65 The screws 16 screw into fixed nuts 18 having small flanges 19 secured by rivets 20 to the flange 8 of the disc. To better accommodate the fixed nuts 18, the flange 10 of the disc is wanting at the immediate location of the nuts 18.

70 The construction I have shown permits the use of a standard quick detachable rim to be mounted on a disc without any additional fastening outside of the screws or bolts, and thus saves the weight of those features of mounting.

75 The fastening is desirable and is used on many wheels not of the disk type.

What I claim is:—

80 1. In a device of the class described, a disc forming a main web of the wheel and having its outer margin turned over into a flange inclined at an angle to the medial plane of the wheel and supporting on this 85 flange a pneumatic tire rim using the inclined wall of the snap ring gutter of the rim as a seat, and a plurality of bolts passing through the snap ring and the gutter of the rim and into lugs fastened to the rear 90 face of the inclined margin of the disc.

95 2. The combination with a pneumatic-tire rim having near one side of the tire seat a marginal gutter provided with a series of perforations, of a detachable side ring held in the gutter and having a series of perforations registering with those of the latter, a wheel body having an inclined peripheral flange fitting and detachably secured to the rear face of the gutter wall, lugs carried by the rear side of said flange, and bolts securing together the gutter, side ring, and lugs; whereby the rim and tire form a unit 100 detachable from the body.

105 3. In a device of the class described, a wheel body adapted to carry a demountable rim of the quick detachable type having a detachable snap ring as a detachable flange held in the main rim portion by means of a gutter, and a series of bolts passing through 110

the side ring and gutter and adapted to secure the rim to the margin of the wheel.

4. In a device of the class described, a wheel body adapted to carry a demountable rim of the quick detachable type having a snap ring as a detachable flange held in the main rim portion by means of a gutter; a series of bolts passing through the side ring and the gutter and adapted to secure the rim to the margin of the wheel, the said side flange and a portion of the main rim pierced and counterbored for seating said bolts.

5. In a device of the class described, a main rim body having a gutter on one edge adapted to sustain in place a detachable snap ring, a series of perforations in the said snap ring and the said gutter adapted to permit of the passage therethru of a

series of bolts for clamping the assembled rim to the margin of the wheel.

6. In a device of the class described, a disc forming the web of the wheel and provided with an inclined flange on its margin adapted to carry on said flange a demountable rim, a series of bolts passing through a portion of the rim and through the said inclined margin of the disc stiffened between the said bolts by a marginal flange substantially parallel with the tread of the rim. 30

Signed at Chicago, in the county of Cook and State of Illinois, this 16th day of October, 1922.

WILLIAM ERASTUS WILLIAMS.
